(57) **CLAIM**

The ornamental design for an eyewear viewing device, as shown and described.

DESCRIPTION

FIG. 1 is a front perspective view of the eyewear viewing device in the present invention with the electronic viewer portion.

FIG. 2 is a front view thereof.

FIG. 3 is a rear view thereof.

FIG. 4 is a top view thereof.

FIG. 5 is a bottom view thereof.

FIG. 6 is a left side view thereof.

FIG. 7 is a right side view thereof; and,

FIG. 8 is a rear perspective view thereof.

The eyewear viewing device in the present invention is an electronic eyewear viewing device having the appearance of glasses, eyewear, eyeglasses or goggles, and includes a glasses, eyewear, eyeglass oroggle portion, an electronic viewer portion with an electronic display for generating electronic images for viewing by the wearer, and including speakers for generating sound.

1 Claim, 5 Drawing Sheets
